PULPSTONE

Walter F. Beth, Worcester, Mass., assignor to Norton Company, Worcester, Mass., a corporation of Massachusetts

Application May 31, 1955, Serial No. 511,832

6 Claims. (Cl. 51—206.5)

The invention relates to pulpstones.

One object of the invention is to provide a pulpstone the blocks of which are not under strain but which are nevertheless held to the center with little possibility of play developing. Another object of the invention is to provide a pulpstone especially adapted for use in grinders of more than usual horsepower. Another object is to provide a pulpstone of rugged characteristics able to withstand heavy duty. Another object is to provide a superior pulpstone having a steel center which can be used for reconstruction after the pulpstone has worn out. Another object is to provide a pulpstone construction permitting the ready replacement of broken blocks.

Other objects will be in part obvious or in part pointed out hereinafter.

In the accompanying drawings illustrating the invention,

Figure 1 is a fragmentary view, partly in end elevation and partly in section, of a pulpstone constructed in accordance with the invention,

Figure 2 is a view similar to Figure 1 illustrating a slight modification of Figure 1,

Figure 3 is a sectional view illustrating one manner of setting the bolts in the blocks,

Figure 4 is a bottom view of one type of block used in making the pulpstone,

Figure 5 is a bottom view of another type of block used in making the pulpstone,

Figure 6 is a side elevation of the pulpstone and its mounting,

Figure 7 is an end elevation of the pulpstone and its mounting,

Figure 8 is a developed view of the pulpstone.

As conducive to a clearer understanding of the present invention, it is noted that many pulpstones were manufactured, sold and used, and patents illustrating and describing them were issued, in which the blocks, also called segments, were secured to a steel drum by bolts of various kinds. As the performance demanded of these pulpstones increased, by the use of driving motors in the pulp grinders of greater horsepower, breakage of the blocks became serious. To meet this situation the concrete center pulpstones were developed and, in many different forms, were manufactured, sold, used and patented. An excellent example of a concrete center pulpstone is illustrated and described in U. S. Patent No. 2,421,885 to Howe and Washburn.

In the case of the steel or iron drum center stones, so far as I am aware the bolts holding the blocks to the center were always tightened to exert initial pressure or tension on the blocks. In the Howe and Washburn patent pulpstone the bolts exert no initial tension on the blocks and are themselves under no initial tension or strain. I have discovered that a superior pulpstone for use in grinders of more than average horsepower can be produced by the utilization of a steel or iron drum center, bolts under initial tension and blocks not under initial tension.

Referring now to Figures 1 to 5 inclusive, the bolts are

2

designated by the reference character 10. Each bolt has threaded heads 12 of the type disclosed in the Howe and Washburn patent, these threaded heads having large rounded threads 14 leaving large rounded grooves 15 between convolutions of the threads. Illustratively the grooves 15 have a radius of .115". The pitch of the threads should be at least .080" but in the illustrative embodiments it is .5" and the threaded ends 12 are 2.25" long.

10 The grooves 15 and consequently the threads 16 of abrasive material of threaded holes 17 which fit therein are preferably somewhat larger than the metal threads 14. The formation of the threaded holes in the pulpstone blocks 19 and 20 is described in the Howe and Washburn patent and hence need not be repeated herein. The blocks 19 and 20 are made of vitrified bonded abrasive material the nature of which is now fully understood in the art. For pulpstone blocks both fused aluminum oxide and silicon carbide have been used and each is used today. 15 The desired abrasive is mixed with ceramic bonding material usually involving a major portion of clay, the blocks are molded from the mixture of abrasive and ceramic material and are then vitrified in a kiln. Such manufacture being well known it need not be further herein described.

In the embodiments of the invention illustrated in the drawings the pulpstone blocks 19 and 20 are secured to a steel drum 21 by means of the bolts 10 as shown. Broadly speaking the drum 21 is a metal drum and any suitable steel or cast iron could be used or other metals such as bronze could be used. However, for manufacturing reasons I prefer to use a cast iron of the kind known as semi-steel. Strength is, of course, important and so is manufacturing cost.

20 The drum 21 is a hollow metal cylinder. Any suitable mounting apparatus can be used, many being known in the art, and if desired the drum 21 can have spokes, or flanges can be used removably to secure it to the shaft of the pulp grinder. The blocks 19 and 20 can be of any desired contour in development, rectangles, squares and hexagons being common. However, as shown in Figures 4, 5, 6 and 8, the blocks 19 inwardly of the stone are regular hexagonal blocks 19 while the marginal blocks 20 are five sided as shown. By this construction the ends of the pulpstone can be plane surfaces or other surfaces of revolution. The outer surfaces of the blocks will be at least eventually cylindrical and preferably the inner surfaces will also be cylindrical. As shown in Figure 5 the bolts 10 are located in the exact centers of the blocks 19. As shown in Figure 4 the bolts 10 are located in the approximate centers of the blocks 20 being on a center line between the two parallel sides and close to the center of gravity. They are centrally located in the blocks 20 as well as in the blocks 19.

25 Referring now to Figure 3, I insure the normal alignment of the bolts 10 by assembling each bolt with an inner washer 25, a pipe 26, and a nut 27 on the outer threaded end 28 of the bolt 10. The nut 27 is tightened and thrusts the washer 25 against the threaded head 12 (which has a shoulder) and as the bolt 10 including the head 12 was carefully machined, the washer 25 will have a surface perpendicular to the axis of the bolt 10.

30 Prior to screwing the heads 12 of the bolts 10 onto the holes 17, I set the blocks 19 and 20 with the holes 17 up and fill the holes 17 with liquid resin which is poured off after a short time to allow it to penetrate into the abrasive somewhat. Then the heads 12 are screwed into the holes 17 by using the nuts 27. The heads 12 are screwed into the holes 17 until the washers 25 contact the blocks 19 and 20 which happens before the heads 12 contact the ends of the holes 17 and thus the washers act as aligning devices properly to align each bolt 10. At this time I

avoid excessive tightening of the bolts 10 in order to avoid placing the abrasive under strain. Then the blocks 19 and 20 are placed in an oven and cured to set the resin. Any suitable resin can be used but I have found that liquid stage phenol-formaldehyde resin mixed with a filler, for example 50% of silica fines, gives very good results. Curing of this resin is well known and illustratively can be at a top oven temperature of about 150° C. During the curing of the liquid resin to form solid resin, any strains between the threaded heads 12 and the abrasive are relieved so that when the blocks come out of the oven the bolts 10 are set therein without any substantial pre-tension.

The drum 21 has holes 31 extending therethrough in radial directions and spaced the proper distance apart to receive the bolts 10 of all the blocks 19 and 20 required to build the pulpstone. For constructing the pulpstone of Figure 1 which is further illustrated in Figures 6, 7 and 8, I provide elastic stop nuts 32 and utilize the washers 25 which fit in flat recesses 33 formed in each of the blocks 19 and 20. I further provide a room temperature cement and I have found that an epoxy resin which is bisphenol epichlorhydrin resin for example sold under the trademark Araldite is satisfactory and the best one known to me. Before setting any block in place the nuts 27 are removed and so are the sleeves 26. Before painting an area of the drum 21 with the cement, I mask off areas around the holes 31 equal to the size of the washers 25 and this may be done with any masking paper or cloth cut into discs and many suitable materials are known. I paint only a limited part of the drum since the cement mentioned sets in twenty or thirty minutes and I want to set the blocks in place before the cement has set.

Having painted a limited area of the drum, and having removed the nuts 27 and the pipes 26 from the bolts 10 of a sufficient number of blocks 19 and 20 to cover the area painted, I remove the masking discs not shown and put the blocks 19 and 20 in place with the bolts 10 through the holes 31, then place the elastic stop nuts on the bolts 10 inside of the drum 20 and tighten them with a torque of about 100 foot pounds which is found to be a good torque and sets a pre-tension in the bolts 10 with a suitable pitch of the threads 28 of around 6,000 pounds actual tensile stress which, however, is on the bolts 10 as the heads 12 and the washers 25 keep the tensile stress from the blocks 19 and 20. This procedure is repeated over and over again until the entire stone has been built by masking a number of areas around the holes 31, painting a limited area with cement, placing 50 blocks 19 or 20 in position with the bolts 10 through the holes 31, then applying and tightening the nuts 32. Instead of stop nuts 32 I might use a nut with lock washers or a pair of nuts as desired. The tensile stress in the bolts 10 and absolute units should be at least 3,000 pounds and not more than the bolts can stand.

Contrary to the usual practice I contemplate no filler between blocks on any sides thereof. Perfect fitting being impractical, there is a clearance 35 between adjacent blocks and I find one sixteenth of an inch to be a practical clearance. Of course in some cases the blocks might touch leaving a greater clearance on opposite sides of each but I prefer to employ small strips of wood as spacers during assembly to keep the clearances approximately equal. In use the clearance spaces will be partially filled with pulp.

I prefer to have only one bolt 10 for each block 19 and 20 but within the scope of the invention in one aspect more can be used. With only one bolt per block the blocks can be quite small relative to the sizes of the drum 21. Replacement of broken blocks then becomes an easy matter especially when no filler between blocks is provided.

One advantage of the pulpstone construction of this invention is that, when the abrasive of the blocks 19

and 20 has been used right down to the tops of the threaded heads 12 of the bolts 10, the pulpstone can be reconstructed in the paper mill without shipping the drum 21 back to the manufacturer. The nuts 32 are removed, then the worn out blocks 19 and 20 can be removed using hammers to loosen them, whereupon the cement on the outer surface of the drum 21 can be cut off and then a new stone can be built by the procedure already described.

Figures 6, 7 and 8 show an illustrative manner of mounting the pulpstone of the invention. Shafts 40 and 41 having flanges 42 are bolted by bolts 44 to a center 21 at the end thereof. Preferably the flanges 42 have inwardly projecting cylindrical portions 46 nicely fitting the insides of the drum 21 to support it accurately. The shafts 40 and 41 are mounted in bearings in the pulpstone grinder. One of these shafts such as the shaft 41 is a driving shaft and has a driving flange 48 secured thereto as by means of a key and the flange 48 is coupled to the motor of the pulp grinder. These features are given only by way of illustration and may be varied at will.

In the modification of Figure 2, the washers 25 are not utilized after the bolts 10 are set in the blocks 19 and 20 although they are utilized to align these parts as already described. The shoulders of the slightly longer heads 12a contact the drum 21 and allow the nuts 32 to put the bolts 10 under the required tensile stress without stressing the threads 14 against the abrasive threads 16. In this case since the area of contact between the heads 12 and the drum 21 is so small the masking can be dispensed with. Figures 4 to 8 inclusive as well illustrate the pulpstone constructed according to the slight modification of Figure 2 as they do the pulpstone according to Figure 1.

In all embodiments of the invention the heads 12 and 12a or equivalent are unstressed relative to the pulpstone blocks when the pulpstone is completed and thereafter when it is not running. This is because the cement 34 can flow during the tightening of the nuts 32 and therefore no matter how tight the nuts 32 may be, there is no tension developed of any appreciable significance between the heads 12 or 12a and the blocks 19 and 20 since each block is placed in position before the cement 34 has set and the shoulders of the heads 12 and 12a with or without the washers 25 prevent the blocks from being drawn inwardly far enough to make actual contact with the iron.

With regard to the cement between the blocks and the drum, I may use other room temperature setting organic cements and I can also use room temperature setting mineral cements of any kind. However, inorganic cements might also be used. Portland base cements, especially with an iron filler, are satisfactory. With regard to the resin in the threaded holes in the pulpstone blocks any other organic resin could be used and there are many. Room temperature mineral cements might also be used there.

While as stated pulpstone blocks of other shapes can be used within the broad features of my invention, there is an advantage in using hexagonal blocks with five sided marginal interfitting blocks. This enables me to use small blocks nicely balanced with the bolts centrally located to avoid excessive strains in use and shapes approaching regular hexagons or being such in development or in chordal section are preferred as thereby no developed dimension of a block need be very much greater than any other dimension thereof. As illustrated the blocks 19 are regular hexagons in development (see Figure 8) although for manufacturing reasons it will probably be preferred to have them regular hexagons in sections cut by chordal planes that extend through edges of the blocks which are elements of the outer cylindrical surfaces thereof. In the claims the inner blocks 19 are stated to be hexagons or that they are hexagonal which means that they are such in plan and in development. In stating that the interfitting blocks are five sided blocks,

the linear sides are referred to as the blocks are seen in development.

The inner abrasive unit for the pulpstone of the invention with its holding bolt in the preferred form of the invention may be described as consisting of a regular hexagon block of vitrified bonded abrasive material having a convex cylindrical surface having six plane surfaces extending from said convex cylindrical surface forming three dihedral angles whose apexes are on the concave side of said convex cylindrical surface, said block having one more surface truncating said dihedral angles, and a holding bolt extending into said block through the one more surface, said holding bolt having an enlarged threaded head the thread of which has a pitch of at least .080", said block having a threaded hole to receive said threaded head with which it is in screw threaded engagement, said bolt being in all of the planes that bisect the dihedral angles, said threaded head being cemented into said threaded hole.

The outer abrasive unit for the pulpstone of the invention with its holding bolt in the preferred form of the invention may be described as consisting of a block of vitrified bonded abrasive material having a convex cylindrical surface with five sides four of which are sides of a hexagon and the fifth of which is a straight side, said block having starting from the two sides adjacent the straight side two plane surfaces extending from said convex cylindrical surface forming a dihedral angle whose apex is on the concave side of said convex cylindrical surface, said block having two other sides starting from the cylindrical surface and tapering inwardly, said block having a plane side starting from the straight side of the convex cylindrical surface, said block having one more surface truncating the dihedral angle, and a holding bolt extending into said block through the one more surface, said holding bolt having an enlarged threaded end of the thread of which has a pitch of at least .080", said block having a threaded hole to receive said threaded head with which it is in screw threaded engagement, said bolt being in the plane that bisects the said dihedral angle and located well inwardly of the sides that extend from the cylindrical surface and being centrally located in said block, said threaded head being cemented into said threaded hole.

The blocks 19 and the blocks 20 have, in the preferred form of the invention, the geometrical features described herein and illustrated in the drawings and it is preferred that the surface adjacent the drum 21 be cylindrical preferably with the centrally located recess 33 which has a flat bottom.

It will thus be seen that there has been provided by this invention a pulpstone in which the various objects hereinabove set forth together with many thoroughly practical advantages are successfully achieved. As many possible embodiments may be made of the above invention and as many changes might be made in the embodiments above set forth, it is to be understood that all matter hereinbefore set forth or shown in the accompanying drawings is to be interpreted as illustrative and not in a limiting sense.

I claim:

1. A pulpstone comprising a metal drum having radial holes therethrough at regularly spaced intervals, a set of abrasive pulpstone blocks with threaded holes of shape, size and number to cover the major portion of the outer

surface of said drum leaving however narrow spaces between adjacent blocks, holding bolts with threaded heads with pitch of at least .080" screwed into said threaded holes and in threaded engagement with said blocks, there being at least one bolt for each block and each bolt extending through one of the holes in the drum, and nuts on the bolts inside of said drum said nuts being tightened to place said bolts under absolute stress of at least 3,000 pounds, said threaded heads being held by said drum to stop the tensile stress from extending into the heads and there being substantially no tension between the heads and the blocks with the pulpstone at rest, and room temperature setting cement between the outside surface of the drum and the adjacent surfaces of the blocks.

2. A pulpstone as claimed in claim 1 in which the heads are cemented in the threaded holes in the blocks with cured resin.

3. A pulpstone as claimed in claim 2 in which the inner blocks are hexagons with interfitting marginal five sided blocks, and the bolts are centrally located in the blocks.

4. A pulpstone as claimed in claim 1 in which the inner blocks are hexagons with interfitting marginal five sided blocks, and the bolts are centrally located in the blocks.

5. A pulpstone block and holding bolt therefor consisting of a hexagonal block of vitrified bonded abrasive material having a convex outer cylindrical surface, said block having six plane surfaces extending from said convex cylindrical surface forming three dihedral angles whose apexes are on the concave side of said convex cylindrical surface, said block having one more surface truncating said dihedral angles, and a holding bolt extending into said block through the one more surface, said holding bolt having an enlarged threaded head the thread of which has a pitch of at least .080", said block having a threaded hole to receive said threaded head with which it is in screw threaded engagement, said bolt being in all of the planes that bisect the dihedral angles, said threaded head being cemented into said threaded hole.

6. A pulpstone block and holding bolt therefor consisting of a block of vitrified bonded abrasive material having a convex cylindrical surface with five sides four of which are sides of a hexagon and the fifth of which is a straight side, said block having starting from the two sides adjacent the straight side two plane surfaces extending from said convex cylindrical surface forming a dihedral angle whose apex is on the concave side of said convex cylindrical surface, said block having two other sides starting from the cylindrical surface and tapering inwardly, said block having a plane side starting from the straight side of the convex cylindrical surface, said block having one more surface truncating the dihedral angle, and a holding bolt extending into said block through the one more surface, said holding bolt having an enlarged threaded end of the thread of which has a pitch of at least .080", said block having a threaded hole to receive said threaded head with which it is in screw threaded engagement, said bolt being in the plane that bisects the said dihedral angle and located well inwardly of the sides that extend from the cylindrical surface and being centrally located in said block, said threaded head being cemented into said threaded hole.

7. A pulpstone block and holding bolt therefor consisting of a block of vitrified bonded abrasive material having a convex cylindrical surface with five sides four of which are sides of a hexagon and the fifth of which is a straight side, said block having starting from the two sides adjacent the straight side two plane surfaces extending from said convex cylindrical surface forming a dihedral angle whose apex is on the concave side of said convex cylindrical surface, said block having two other sides starting from the cylindrical surface and tapering inwardly, said block having a plane side starting from the straight side of the convex cylindrical surface, said block having one more surface truncating the dihedral angle, and a holding bolt extending into said block through the one more surface, said holding bolt having an enlarged threaded end of the thread of which has a pitch of at least .080", said block having a threaded hole to receive said threaded head with which it is in screw threaded engagement, said bolt being in the plane that bisects the said dihedral angle and located well inwardly of the sides that extend from the cylindrical surface and being centrally located in said block, said threaded head being cemented into said threaded hole.
